Application November 26, 1952, Serial No. 322,754

7 Claims. (Cl. 260—674)

This invention relates to the separation of aromatic hydrocarbons from a mixture of hydrocarbons. More particularly it relates to the recovery of aromatic hydrocarbons from an olefinic hydrocarbon-free and organic sulfur compound-free petroleum naphtha.

There is a considerable demand for aromatic hydrocarbons, particularly the lower boiling monocyclic aromatic hydrocarbons such as benzene, toluene, xylene and trimethylbenzene. Petroleum fractions are a good source of these aromatic hydrocarbons, particularly those fractions obtained by the catalytic treatment of virgin naphthas, e. g., from the so-called hydroforming process and platforming process.

An object of the invention is the separation of aromatic hydrocarbons from a mixture of hydrocarbons; preferably from a mixture of hydrocarbons that is essentially free of olefinic hydrocarbons and organic sulfur compounds. Another object is the recovery of aromatic hydrocarbons from petroleum distillates, preferably distillates boiling in the gasoline range, i. e., below about 400° F. (200° C.). Yet another object is the recovery of essentially pure aromatic hydrocarbons from a mixture of hydrocarbons. A particular object is the recovery of aromatic hydrocarbons from a mixture of hydrocarbons by treatment of said mixture with an alkanesulfonic acid and a silver salt soluble in the acid. A further object of the invention is the recovery of aromatic hydrocarbons from a solution consisting of said aromatic hydrocarbon and alkanesulfonic acid and a soluble silver salt by displacement therefrom with an added monocyclic aromatic hydrocarbon having a boiling point of not more than about 180° C. A preferred object is the recovery of benzene, toluene and C₈ aromatic hydrocarbons from a hydroformate or platformate which is essentially free of olefinic hydrocarbons and organic sulfur compounds.

The above objects and other objects not set out separately are attained by contacting a hydrocarbon mixture which contains aromatic hydrocarbons and non-aromatic hydrocarbons with a treating agent consisting essentially of a substantially anhydrous alkanesulfonic acid and a silver salt that is highly soluble in said acid, under liquid phase conditions and at operating conditions of temperature and pressure, which treating agent is present in an amount at least sufficient to obtain separate raffinate and extract phases.

An aromatic hydrocarbon can be displaced from the extract phase by contacting the extract phase with a lower molecular weight aromatic hydrocarbon, e. g., trimethylbenzene can be displaced by contacting the extract phase with xylene, toluene or benzene. Thus in the case of an extract phase containing aromatic hydrocarbons with a molecular weight higher (or loosely speaking, higher boiling) than benzene, these aromatic hydrocarbons can be displaced from the extract phase by contacting the extract phase with a sufficient amount of added benzene.

The alkanesulfonic acid of this invention may be any alkanesulfonic acid which can exist as a liquid at a temperature below the decomposition temperature of the

5

10

2

acid. Thus acids having from one to as many as nine or more carbon atoms can be used. For ease in operation it is desirable to operate with alkanesulfonic acids which are liquids at ambient temperatures and which have relatively high decomposition temperatures. The preferred acids are those which have the sulfonic group attached to the end carbon atom of a straight hydrocarbon chain. Because of their melting points and relatively high decomposition points and relatively high boiling points, the preferred alkanesulfonic acids are methanesulfonic acid, ethanesulfonic acid and 1-propanesulfonic acid.

As an example of the thermal stability of the preferred acids, ethanesulfonic acid is unaffected by heating for 4 hours at 120° C. and only 1% is decomposed by heating for 4 hours at 180° C. Methane- ethane- and 1-propane- are the most stable alkanesulfonic acids, in that order.

The boiling points and melting points of the preferred alkanesulfonic acids are given below:

Acid	B. P.		M. P. °C.
	°C.	mm. Hg	
Methane	122	1.0	+20
Ethane	123	1.0	+17
1-Propane	136	1.0	+7

The process of this invention is carried out under liquid phase conditions. Therefore, it is necessary that both the mixed hydrocarbon feed and the alkanesulfonic acid be liquids. Thus the temperature in the contacting zone must be at least high enough to maintain the particular alkanesulfonic acid in the liquid phase. Elevated temperatures can be employed by the use of sufficient pressure to maintain the hydrocarbons in the liquid phase. The maximum temperature of operation must be below the temperature at which appreciable decomposition of the alkanesulfonic acid occurs. The desirable maximum temperature of contacting is about 150° C. Elevated temperatures have an appreciably unfavorable effect on the selectivity of aromatic separation so that temperatures below about 50° C. are desirable. It is preferred to operate at temperatures between about 0° and 30° C. It is to be understood that, even at the preferred range of temperature, the temperature of operation must be high enough to maintain the alkanesulfonic acid in the liquid state.

The presence of water in the alkanesulfonic acid has an adverse effect on the selectivity of the treating agent. Amounts of water up to about 5 weight percent can be present. It is preferred to operate with alkanesulfonic acid that is essentially anhydrous, i. e., the acid should contain less than about 1-2% of water. In order to keep the water content of the acid low, it is preferred to operate with essentially anhydrous feed.

Commercial purity alkanesulfonic acid contains about 1-2% of sulfuric acid. Under the preferred operating conditions of the process the sulfuric acid sulfonates some of the aromatic hydrocarbon in the extract phase.

The presence of arylsulfonic acid in the contacting zone is detrimental because of the formation of solid hydrates. It is preferred to operate with alkanesulfonic acid that is essentially sulfuric-acid free.

The amount of alkanesulfonic acid used in the contacting zone must be at least sufficient to form separate raffinate and extract phases, i. e., the amount of acid present must exceed the solubility of the acid in the mixed hydrocarbon feed. More than this minimum amount should be used, e. g., about 10 volume percent, based on mixed hydrocarbon feed. Quite large amounts of acid may be used, as much as 300 volume percent or more; operation with excessively large amounts results

in a reduction in the purity of the aromatic hydrocarbons in the extract. It is preferred to operate with amounts of alkanesulfonic acid, based on mixed hydrocarbon feed, of between about 50 and 120 volume percent.

It has been discovered that the presence of certain silver salts in alkanesulfonic acid greatly increases the ability of the alkanesulfonic acid to dissolve selectively aromatic hydrocarbons. This increase in solubility is particularly great in the lower molecular weight alkanesulfonic acids, i. e., methanesulfonic acid, ethanesulfonic acid and 1-propanesulfonic acid. The silver salts that are useful for this purpose must have a very high solubility in the particular alkanesulfonic acid. The silver salts of this invention are silver sulfate and silver alkanesulfonate. Preferably, the silver alkanesulfonate should be the salt of the particular alkanesulfonic acid being used in the process, e. g., when using ethanesulfonic acid the silver salt should be silver ethanesulfonic acid. However, it is to be understood that this is not an essential requirement of the process and different salts may be used or mixtures of salts may be used with a particular alkanesulfonic acid or with mixtures of different alkanesulfonic acids. Furthermore, mixtures of silver sulfate and silver alkanesulfonate may be used. It is preferred to operate with at least one member selected from the group consisting of silver sulfate, silver methanesulfonate, silver ethanesulfonate and silver 1-propanesulfonate.

The amount of silver salt present in the treating agent, which treating agent consists essentially of alkanesulfonic acid and the silver salt, may be as little as a trace. The solubility of the silver salt in the alkanesulfonic acid is increased by the presence of aromatic hydrocarbons therein. This is believed to be caused by the interaction of acid, aromatic hydrocarbon and silver salt to form an adduct or complex, which complex is extremely soluble in the acid. However, an upper limit exists on the ability of the acid to dissolve silver salt even in the presence of aromatic hydrocarbon; the presence of silver salt in excess of the amount that can be dissolved in the extract phase does not further improve the ability of the acid to dissolve aromatic hydrocarbons. The upper limit on silver salt usage is the limit of solubility in the extract phase, i. e., the amount of silver salt added to the contacting zone should be such that no separate phase of solid silver salt is present therein. Normally less than this maximum amount of acid will be used. In general it is preferred to operate with 1 gram atom of silver (as silver salt) in the contacting zone per mol of aromatic hydrocarbon in the mixed hydrocarbon feed. The preferred treating agent consists of defined alkane sulfonic acid and defined silver salt, said silver salt being present in an amount that exceeds the physical solubility of said silver salt in said alkane sulfonic acid, i. e., the agent consists of alkane sulfonic acid, physically dissolved silver salt and solid silver salt particles dispersed in said alkane sulfonic acid; this treating agent appears to be a liquid and may be considered as such in operation of a unit.

The feed to the process may be any mixture of hydrocarbons which contains appreciable amounts of aromatic hydrocarbons, preferably monocyclic aromatic hydrocarbons. While any mixture of hydrocarbons can be utilized, it is preferred to operate with mixtures of hydrocarbons derived from petroleum. These may be naturally occurring mixtures derived by distillation from crude oil or they may be derived from the various processes that produce aromatic hydrocarbon-rich fractions, e. g., the hydroformate or platformate products produced by the catalytic treatment of straight run naphthas in the so-called hydroforming and platforming processes. Since the largest demand for aromatic hydrocarbons is for benzene, toluene and xylenes, it is preferred to operate on a hydroformate or platformate containing these aromatic hydrocarbons, i. e., fractions boiling between about 100° and 385° F.

Olefinic hydrocarbons present in the feed react with the treating agent to form esters. These esters are thermally unstable; when the extract phase is heated to distill the aromatic hydrocarbons, the esters decompose and precipitate free-silver. Organic sulfur compounds present in the feed also react with the treating agent to form thermally unstable materials; these materials decompose on heating to precipitate free-silver. In order to avoid the loss of silver salt by these side reactions, it is preferred to operate on a mixed feed which is essentially free of olefinic hydrocarbons and organic sulfur compounds. Many methods of treating a raw feed to remove these undesired compounds are known to the art, e. g., treating with sulfuric acid or with liquid HF.

15 The extract phase obtained by the contacting of the mixed hydrocarbon feed with the treating agent consists of alkanesulfonic acid, silver salt, aromatic hydrocarbons and some non-aromatic hydrocarbons. The amount of non-aromatic hydrocarbon present will be dependent 20 somewhat on the conditions of contacting, i. e., temperature, amount of silver salt, amount of acid, type of acid, type of feed, etc. It has been found that these non-aromatic hydrocarbons can be displaced from the extract phase by washing the extract phase with a hydrocarbon 25 that is inert to the action of the treating agent and preferably is easily separable from the aromatic hydrocarbons by distillation. Examples of suitable inert hydrocarbons are butane, pentane and hexane. Inert hydrocarbons which boil higher than the aromatic hydrocarbons can be used when operating under conditions such that the higher 30 boiling inert hydrocarbons can be recovered from the extract phase by distillation. The amount of inert hydrocarbon used for washing purposes will vary somewhat with the amount of non-aromatic hydrocarbon present in 35 the extract phase. The amount of wash hydrocarbon used should be held to a minimum as the wash hydrocarbon does displace some of the aromatic hydrocarbons. By control of the conditions of washing it is possible to displace the close boiling non-aromatic hydrocarbons 40 with substantially no displacement of aromatic hydrocarbons.

The extract hydrocarbons present in the extract phase can be recovered in several ways: The simplest procedure for experimental purposes involves the dilution of the 45 extract phase with water. The addition of a sufficient amount of water to the extract phase results in the formation of an upper extract hydrocarbon phase and a lower aqueous phase which contains the alkanesulfonic acid and the silver salt. The extract hydrocarbons are separated by decantation and are freed of dissolved and occluded aqueous phase by treatment with aqueous caustic solution.

Another method of separating the extract hydrocarbons from the extract phase involves the neutralization of the 55 alkanesulfonic acid, e. g., by treatment with ammonia or solid caustic; preferably the neutralization is carried out with an aqueous solution of the alkaline agent. The extract hydrocarbon layer can then be decanted from the lower layer of neutralized acid and silver salt.

60 The methods described above are suitable for use with any alkanesulfonic acid because they eliminate the problem of thermal decomposition of the acid.

When operating with mixed feed containing aromatic hydrocarbons which boil, either at normal pressure or 65 under vacuum, at temperatures well below the decomposition temperature of the particular alkanesulfonic acid, the aromatic hydrocarbon can be readily separated from the extract phase by distillation therefrom. The recovered treating agent consists of the alkanesulfonic acid, dissolved silver salt and solid salt. The solid salt exists as extremely fine particles dispersed in the acid. The dispersion is quite stable and does not precipitate solid salt even on standing for several hours. The dispersion of 70 solid silver salt in acid is readily pumpable. In the process 75 of solid silver salt in acid is readily pumpable. In the process

design of a unit, the dispersion can be considered to be a liquid.

Thus benzene can be distilled away from an extract phase consisting of benzene, methanesulfonic acid (or ethanesulfonic acid or 1-propanesulfonic acid) and silver sulfate (or the corresponding silver alkanesulfonate) by heating the extract phase to 150° C., preferably below about 120° C. Trimethylbenzene can be recovered from an extract phase by operating at about 150° C. at about 10 mm. Hg pressure. In order to recover substantially all the aromatic hydrocarbon from the extract phase, it is necessary to operate at a temperature considerably higher than the boiling point of the aromatic hydrocarbon or conversely, at a pressure considerably lower than that predicted from the vapor pressure curve of the aromatic hydrocarbon at the particular temperature of operation.

Still another method for separating the aromatic hydrocarbons from the extract phase has been found. This method is particularly suitable when the aromatic hydrocarbons boil at a temperature such that distillation cannot be used without appreciable decomposition of the alkanesulfonic acid. It is preferred to use this method when the boiling point of an aromatic hydrocarbon at normal pressure exceeds about 180° C., e. g., monocyclic aromatics containing 10 or more carbon atoms. When operating with the preferred alkanesulfonic acids no appreciable decomposition will occur when distilling, under vacuum, the extract phase at a temperature corresponding to 180° C. at normal pressure, i. e., 760 mm. Hg; however, to minimize the risks inherent in operating so near the appreciable decomposition temperatures, it is preferred to use the "displacement technique" with all alkanesulfonic acids when one of the aromatic hydrocarbons in the extract phase boils above about 180° C. at normal pressure.

It has been found that an aromatic hydrocarbon can be displaced from the extract phase by contacting the extract phase with an added lower molecular weight aromatic hydrocarbon. To illustrate, trimethylbenzene can be displaced by xylene, and toluene can be displaced by benzene. It is preferred to use as the displacing aromatic hydrocarbon a monocyclic aromatic hydrocarbon which has a boiling point of not more than about 180° C. at normal pressure and preferably boils below or at the same boiling point as the lowest boiling aromatic hydrocarbon present in the extract phase. For example, in the case of an extract phase containing benzene and higher boiling aromatic hydrocarbons, the displacing hydrocarbon should be benzene. In the case of an extract phase containing toluene and higher boiling aromatic hydrocarbons, the displacing hydrocarbon should be either toluene or benzene.

The amount of displacing hydrocarbon is dependent somewhat on the type of hydrocarbon being displaced and also upon the efficiency of the contacting operation. When operating with an efficient countercurrent contacting zone at a temperature between about 0° and 30° C., an extract phase containing xylene as the sole aromatic hydrocarbon should be contacted with between about 5 and 7 mols of benzene per mol of xylene in order to displace about 95% of the xylene. By using a sufficient number of extract stages in the countercurrent contacting, as much as 99% of the xylene can be displaced using this amount of benzene. In order to obtain a 95% displacement of xylene in the extract phase, it is necessary to use between about 10 and 15 mols of benzene per mol of xylene when using a single batchwise contacting operation. The amount of displacing hydrocarbon needed in any particular case can be readily determined by experiment.

A preferred embodiment of the process of this invention is illustrated in the annexed figure which forms a part of this specification. The embodiment illustrated is

schematic in nature and many items of process equipment have been omitted. These items may be readily added thereto by those skilled in the art.

Feed from source 11 is passed through line 12 into mixer 13. The feed in this illustration consists of the fraction boiling between about 100° and 385° F. derived by the distillation of a hydroformate product. This fraction contains about 45 volume percent of benzene, toluene, ethylbenzene, xylene, C₉ aromatic hydrocarbons and C₁₀ aromatic hydrocarbons. In addition the feed contains about 1% of olefinic hydrocarbons and about 0.03 weight percent of sulfur; the remainder consists of paraffinic and cycloparaffinic hydrocarbons.

It is desired to remove the olefinic hydrocarbons and the organic sulfur compounds from this feed prior to separating the aromatic hydrocarbons.

In this illustration the olefinic hydrocarbons and organic sulfur compounds are removed by treating the feed with sulfuric acid. From source 16, 98% sulfuric acid is

20 passed through line 17 into mixer 13. Five pounds of H₂SO₄ are used per barrel (42 gal.) of feed. Mixer 13 is provided with heat exchange coil 18 which maintains the temperature of the contents of the mixer at about 20° C. The H₂SO₄ and the feed are thoroughly agitated 25 in mixer 13 for a time long enough to remove the olefinic hydrocarbons and organic sulfur compounds, but not long enough to sulfonate any of the aromatic hydrocarbons. A suitable contacting time is 5 minutes.

From mixer 13 a mixture of treated feed and acid 30 sludge is passed through line 21 into settler 22. In settler 22 a lower layer of sludge is separated and withdrawn to sludge disposal by way of line 23. An upper layer of treated feed is withdrawn from settler 22 by way of line 24 and is passed into mixer 26.

35 Aqueous caustic, 10% NaOH, in an amount of about 50 volume percent based on treated feed is passed from source 27 through line 28 into mixer 26. The aqueous caustic and treated feed are thoroughly intermingled in mixer 26 for a time sufficient to neutralize the acid dissolved and occluded in the treated feed. The contents of mixer 26 are passed by way of line 31 into settler 32.

40 A lower aqueous layer of waste caustic is withdrawn from the settler 32 and is passed to waste disposal by way of line 33. An upper neutral feed layer is withdrawn from settler 32 and is passed by way of line 34 into drier 36.

45 Drier 36 is a vessel filled with a medium for removing dissolved and occluded aqueous caustic from the neutral feed. Drier 36 may be filled with steel wool, rock salt, alumina balls, etc. Herein drier 36 is filled with alumina balls. Dried feed essentially free of water is withdrawn from drier 36 by way of line 37. Periodically drier 36 is revivified by methods well known in the art.

50 The essentially olefinic hydrocarbon and organic sulfur compound-free feed in line 37 is passed through heat exchanger 39 and line 41 into extractor 42. Extractor 42 is a continuous countercurrent extraction tower which provides about five theoretical extraction stages. Extractor 42 may be filled with acid-resistant packing such as Raschig rings, Berl saddles, etc., or may be equipped with bubble trays or sieve plates. In this embodiment all the equipment exposed to alkanesulfonic acid is made of type 304 stainless steel.

55 Extractor 42 in this illustration is maintained at a temperature of 30° C. However, the extractor may be provided with heat exchangers so that a temperature gradation may be maintained over the height of the tower.

70 Methanesulfonic acid from source 46 is passed through line 47 into vessel 48. Silver methanesulfonate from source 51 is passed through line 52 into vessel 48. In vessel 48 the silver salt is mixed with the acid and the temperature of the treating agent is adjusted to that desired in the extractor. Herein 70 volume percent of methanesulfonic acid is used based on feed from line 75

41; and 1 g. atom of silver is used per mol of aromatic hydrocarbon present in the feed from line 41. The treating agent is passed from vessel 48 by way of line 54 into an upper point of extractor 42. Extractor 42 is operated with the interface slightly below the point of treating agent entry, i. e., high level operation.

Extractor 42 is operated so that about 10 minutes of contacting time is obtained in each extraction stage or a total residence time of about 1 hour. The raffinate phase containing dearomatized oil, dissolved treating agent and occluded treating agent is withdrawn from extractor 42 and passed by way of line 56 into separator 57. In separator 57 occluded treating agent is removed from the raffinate phase and is returned to extractor 42 by way of line 58. The raffinate phase from separator 54 is passed by way of line 61 into washer 62.

Washer 62 is a countercurrent contacting tower provided with packing to permit efficient contacting of the raffinate phase and water. Water from source 63 is passed through line 64 into an upper point of washer 62. About 1 volume of water is used per volume of raffinate phase. The temperature of washing is about that of the wash water. Oil essentially free of alkanesulfonic acid is withdrawn from washer 62 by way of line 66 and sent to storage not shown. This oil has a high octane number and is suitable for aviation gasoline blending stock. The water and acid are withdrawn from washer 62 and are passed through line 67 to acid recovery facilities not shown. The acid can be recovered by multiple-effect distillation by methods well known to this art.

In order to remove the close boiling non-aromatic hydrocarbons from the extract phase an inert wash hydrocarbon is introduced near the bottom of extractor 42. In this illustration the wash hydrocarbon is pentane which is passed from source 71 and line 72 into extractor 42 near the bottom thereof; 20 volume percent based on hydrocarbons in the extract phase is introduced into extractor 42. The pentane in part remains in the extract phase and in part passes out of extractor 42 in the raffinate phase. This latter portion is recovered along with the raffinate hydrocarbons and is passed to storage there-with by way of line 66.

The extract phase is withdrawn from extractor 42 by way of valved line 73 and is passed through heat exchanger 76 and line 77 into a hydrocarbon recovery vessel 78. Vessel 78 is provided with an internal heat exchanger 79. Vessel 78 is operated at a bottoms temperature of about 130° C. and at a pressure of 300 mm. Hg. Substantially all the benzene and toluene present in the extract phase are removed overhead and are passed through line 81, vacuum pump 82, line 83 and heat exchanger 84 into valved line 86. The benzene and toluene are condensed in heat exchanger 84 and are passed as liquids into line 86.

The bottoms from vessel 78 are passed by way of valved line 91 through heat exchanger 92 and line 93 into extractor 94. Heat exchanger 92 reduces the temperature of the bottoms from vessel 78 to a temperature of about 25° C. Extractor 94 is a vessel similar in construction to extractor 42 and provides about five theoretical extraction stages.

Benzene from line 96 is introduced into extractor 94 near the bottom thereof. In this illustration 6 mols of benzene are used per mol of aromatic hydrocarbon present in line 93. A second raffinate phase consisting of benzene, C₉ and C₁₀ aromatic hydrocarbons is withdrawn from the top of extractor 94 and is passed by way of line 98 into line 86. The combined stream of benzene and toluene from vessel 78 and the raffinate phase from extractor 94 are passed through line 99 into fractionator 101.

Fractionator 101 is provided with internal heat exchanger 102. Fractionator 101 represents a schematic distillation system to separate the contents of line 99 into its major components. Pentane is passed by way of line

104 and other lines not shown to line 72 for reuse in the process. The toluene is passed to storage not shown by way of line 106. Mixed C₈ aromatic hydrocarbons are passed to storage not shown by way of line 107. A bottoms fraction consisting of C₉ and C₁₀ aromatic hydrocarbons and trace amounts of alkanesulfonic acids are passed to storage not shown by way of line 108. This fraction can be readily free of acid by a washing operation such as shown in washer 62 and then separated into close boiling fractions by distillation.

Benzene is withdrawn from the fractionation system by way of line 111. A portion of the total benzene is passed by way of valved line 112 and line 113 into line 96 for use in extractor 94. The remainder of the benzene from line 111 is sent to storage not shown by way of line 116.

The second extract phase from extractor 94 is passed through line 118, heat exchanger 119 and line 121 into benzene recovery vessel 122. Vessel 122 is provided with an internal heater 123. Vessel 122 is operated at a temperature of about 110° C. and a pressure of about 300 mm. Hg. The benzene vapors are passed out of vessel 122 through line 126, vacuum pump 127 and line 128 into heat exchanger 129. The vapors are condensed in heat exchanger 129 and are passed by way of lines 131, 113 and 96 into extractor 94.

The bottoms from vessel 122, which consist essentially of a fluid dispersion of solid silver methanesulfonate in a solution of methanesulfonic acid and silver methanesulfonate is withdrawn from vessel 122 and recycled to extractor 42 by way of lines 134 and 54.

It is to be understood that the partial removal of benzene and toluene from the first extract phase in vessel 78 is not essential. The entire extract phase could be passed into extractor 94. However, in order to reduce the amount of benzene circulating, it is preferred to remove the benzene and toluene before the displacement operation.

In order to illustrate the results obtainable with this process, several series of runs were made under different conditions. In all these runs the extraction was carried out by simple shaking in a separatory funnel. In each run the feed consisted of 25 ml. of a mixture of n-heptane and a particular aromatic hydrocarbon. The feed consisted approximately of equal volumes of the two components. In each run 20 ml. of the particular alkanesulfonic acid was used and the contacting was carried out at room temperature, about 20° C. The procedure consisted of adding the silver salt, the acid and the feed to the contacting vessel, in that order. After the contacting step the contents were settled and the phases separated. The raffinate phase was washed with aqueous caustic solution and the composition determined by refractive index methods. This extract phase was diluted with water and the extract hydrocarbon recovered. The composition of the extract hydrocarbons was determined by refractive index methods.

TEST 1

In this test a series of runs was made to determine the improvement in extraction obtainable by the addition of silver sulfate to a particular alkanesulfonic acid when using various aromatic hydrocarbons in the mixed feed. Each run was carried out as described above. Comparative runs were made at each set of conditions; one run without silver sulfate, and the other run containing 0.035 g. atoms of silver. The results of these runs are given in Table I.

The data show that with methanesulfonic acid a several-fold improvement in extraction efficiency is obtained by the presence of silver sulfate in the acid. The "net mols of aromatics extracted per gram atom of silver" were calculated by subtracting from the total aromatics extracted when using silver salt, the aromatics extracted by the acid alone.

¹ Silver sulfate.² Silver ethanesulfonate.

TEST 2

In this test a series of runs was made using in all runs the same feed and ethanesulfonic acid. The amount of silver sulfate present was varied in order to determine the effect of silver sulfate concentration on the extraction efficiency. The results of this test are shown in Table II.

The data show that within experimental error the amount of aromatic hydrocarbon extracted per gram atom of silver is constant over a range of silver salt usage. Also that increasing the silver salt usage improves the selectivity of the extraction.

TEST 3

In this test a series of runs were made using the same feed, two different acids and using in one instance silver sulfate, and in the other instance silver ethanesulfonate as the silver salts. The purpose of these runs was to determine any difference in extraction efficiency based on difference in type of silver salt. The data presented in Table III indicate that silver ethanesulfonate is somewhat better than silver sulfate for the extraction of benzene from a benzene-heptane feed.

TEST 4

In this test m-xylene was displaced from an extract phase by contacting the exact phase with benzene. The extract phase was made up by adding 0.136 mol of m-xylene and 0.062 g. atoms of silver as silver sulfate to 25 ml. of methanesulfonic acid. In each run the standard extract phase was agitated with different amounts of benzene. The raffinate hydrocarbons and extract hydrocarbons were recovered and analyzed for m-xylene and benzene content. The results of this single-stage batchwise

contacting show that an added lower molecular weight aromatic hydrocarbon can displace a higher molecular weight aromatic hydrocarbon from an extract phase. The results of this test are shown in Table IV.

Table IV

Run	Added Benzene (Mols/Mols Xylene)	Raffinate		Extract	
		V. percent m-Xylene	V. percent Benzene	V. percent m-Xylene	V. percent Benzene
20	1	100	0	80.5	19.5
21	3	84	16	51.2	48.8
22	5	46	54	31.7	68.3

TEST 5

In this test 25 ml. of a feed mixture consisting of 33 weight percent butylbenzene, 22 weight percent naphthalene and the remainder n-heptane was contacted with 20 ml. of ethanesulfonic acid and 0.021 g. atom of silver as silver sulfate at 20° C. Analysis of the raffinate hydrocarbons and extract hydrocarbons indicated that naphthalene was preferentially taken into the extract phase. The separation factor α , between butylbenzene and naphthalene, for this run was 17. This test indicates that by the use of the alkanesulfonic acid-silver salt treating agent of this invention it is possible to readily separate dicyclic aromatic hydrocarbons from monocyclic aromatic hydrocarbons.

Thus having described the invention, what is claimed is:

- An aromatic hydrocarbon separation process comprising (1) countercurrently contacting under essentially anhydrous conditions at a temperature between

about 0° C. and 150° C. a feed consisting essentially of aromatic hydrocarbons and saturated non-aromatic hydrocarbons, said hydrocarbons boiling below about 450° F. with a treating agent consisting of (a) an alkanesulfonic acid having from 1 to 9 carbon atoms and (b) a silver salt selected from the class consisting of silver sulfate and silver alkanesulfonates containing from 1 to 9 carbon atoms wherein said acid is present in an amount between about 50 and 120 volume percent based on said feed and said silver salt is present in an amount of at least about 1 gram atom of silver per mol of aromatic hydrocarbons in said feed, which treating agent contains said silver salt in an amount that exceeds the physical solubility of said silver salt in said alkanesulfonic acid, whereby said treating agent consists of said alkanesulfonic acid, physically dissolved silver salt and solid silver salt particles dispersed in said alkanesulfonic acid, the treating agent appearing to be a liquid, (2) separating a raffinate phase from an extract phase comprising treating agent and aromatic hydrocarbons, (3) removing essentially all the hydrocarbons from said extract phase by a distillation procedure to recover treating agent consisting of alkanesulfonic acid, physically dissolved silver salt and solid silver salt particles dispersed in said alkanesulfonic acid, the whole appearing to be a liquid, and (4) recycling said recovered treating agent to said contacting zone.

2. The process of claim 1 wherein said temperature is between about 0° C. and 30° C.
3. The process of claim 1 wherein said acid is selected from the class consisting of methanesulfonic, ethanesulfonic, and 1-propanesulfonic.
4. The process of claim 1 wherein said feed is a catalytic reformate boiling over the range of about 100° F. to 385° F.
5. The process of claim 3 wherein said salt is silver 10 methanesulfonate.
6. The process of claim 3 wherein said salt is silver ethanesulfonate.
7. The process of claim 3 wherein said salt is silver sulfate.
